UNITED STATES PATENT OFFICE.

CHARLES F. HENDERSON AND CHAUNCEY D. WINCHELL, OF WAMPSVILLE, NEW YORK.

THIRD-RAIL SNOW-CLEANER.

1,181,883.

Specification of Letters Patent.

Patented May 2, 1916.

Application filed November 6, 1915. Serial No. 60,096.

To all whom it may concern:

Be it known that we, CHARLES F. HENDERSON and CHAUNCEY D. WINCHELL, citizens of the United States, residing at 5 Wampsville, in the county of Madison and State of New York, have invented new and useful Improvements in Third-Rail Snow-Cleaners, of which the following is a specification.

10 This invention relates to devices for removing snow and ice from the third rail of rapid transit systems and it consists in the novel features hereinafter described and claimed.

15 An object of the invention is to provide a cleaner or plow as indicated which is of simple structural arrangement and adapted to be carried by a car truck and which is provided with a scraper blade adapted to 20 move along the underside of the third rail and remove the snow and ice therefrom. The said scraper blade is mounted upon a chute into which the material removed from the third rail may fall and from which 25 it is ejected over and beyond the said rail. The chute is mounted upon an arm which in turn is pivotally mounted in a bracket attached to the truck frame of the car or vehicle, and means are provided at the said 30 bracket for holding the arm and the chute carried thereby in an elevated position with relation to the third rail when the device is not in use. Also means are provided at the said bracket for resiliently holding the 35 chute and the scraper blade toward the third rail when the device is in use for the purpose stated.

In the accompanying drawings: Figure 1 is a side elevation of a car truck with 40 the cleaner applied. Fig. 2 is a top plan view of the same. Fig. 3 is a front elevation of the same showing the parts in one position. Fig. 4 is a similar view showing the parts in another position. Fig. 5 is a 45 side elevation of the bracket of the cleaner. Fig. 6 is a plan view of the same. Fig. 7 is a vertical sectional view of the same. Fig. 8 is a horizontal sectional view of the same. Fig. 9 is a longitudinal sectional view of 50 the blade of the device and adjacent parts. Fig. 10 is a transverse sectional view of the same.

As illustrated in the accompanying drawings the snow and ice cleaner is applied to a 55 car truck 1, which may be of any usual or conventional form. A bracket 2 is mounted

at the side of the truck 1 and may be in the form of a casting or any other suitable structure. An arm 3 is pivotally mounted in the bracket 2 and at its other end the 60 said arm is bifurcated forming branches 4. A chute 5 is attached to the outer ends of the branches 4 and the said chute is of general tubular configuration. The chute 5 is provided at its lower or forward end with an 65 extension 6 which constitutes a nose adapted to travel under the third rail 7 when the device is in use for removing snow or ice from the underside of the same. The chute 5 is curved longitudinally and when 70 it is in use for removing the material from the third rail, the upper end of the said chute is disposed above the third rail with its outlet openings so positioned as to discharge the material over the third rail and 75 beyond the side thereof. Guide strips 8 are mounted upon the upper side of the nose 6 and the said nose is provided at a point between the said guide with an opening 9. A scraper blade 10 is detachably 80 mounted upon the nose 6 between the guide strips 8 and the said blade 10 is convexed longitudinally and is provided at a point between its ends with an opening 11 which is located above and slightly in advance 85 of the opening 9 in the nose 6.

The arm 3 is provided at its inner end with an angularly disposed extremity 12 having at its rear side a rearwardly disposed shoulder or lug 13. A block 14 is 90 movably mounted in the bracket 2 and a coil spring 15 is interposed between the top portion of the said bracket and the upper surface of the block 14 and is under tension with a tendency to hold the block 15 in a 95 lowered position in the bracket 2. The block 15 is provided at its opposite side with lugs 16 which lie in vertically disposed slots 17 provided in the sides of the bracket 2 whereby the block 14 is guided in its vertical movement and the vertical movement of the said block is limited by the length of the slots 17. The arm 3 is provided at a point in the vicinity of the edge of the bracket 2 with a notch 18 which, when the 100 said arm is swung to an upright position with relation to the bracket, is received between the opposite sides of the bracket. A spring pressed dog 19 is pivotally mounted upon one side of the bracket 2 and has an 110 end portion passing through one side of the bracket and the end of the said dog is

adapted to enter the notch 18 when the arm 3 is swung to a vertical position with the relation to the bracket 2 whereby the said arm and its attachments are held at a set position. The block 14 is provided at its underside with a socket 20 in which the upper end of the extremity 12 is adapted to engage when the arm 3 is swung to its lowered position with relation to the bracket 2. 5
10 and inasmuch as the spring 15 bears against the said block 14 it will be seen that the arm 3 is held resiliently under the influence of the spring 15 in its lowered position. A pawl 21 is pivotally mounted in the lower portion of the bracket 2 and a spring 22 is mounted in the said bracket and bears at its free end against one side of the pawl 21 and is under tension with a tendency to hold the free end of the pawl 21 toward 15
20 the extremity 12 of the arm 3. The pawl 21 is provided at one side with a knob 23 which passes through a slot 24 provided in the side of the bracket 2.

The operation of the device is as follows: 25 The arm 3 is swung to its lowered position with relation to the bracket 2 and when so swung the lower end of the two sides lies below the third rail 7 and inasmuch as the arm 3 is resiliently supported under the influence of the spring 15, the upper side of 30
35 the blade 10, bears against the lower face of the third rail 7, consequently as the truck 1 moves along the track the chute 5 is carried along the third rail and the blade 40
45 10 moves the snow and ice from the lower face of the rail 7. The material thus removed from the third rail gravitates through the openings 11 and 9 and falls in the lower end of the nose 6. As the material accumulates in the said nose it is crowded up through the chute 5 and from the upper end of the said chute is delivered above and beyond one side of the third rail 7. Therefore, it will be seen that as the truck moves 50
55 along the track the blade carried by the chute 5 efficiently cleans the lower surface of the said third rail in order that it may have proper contact with the shoe of the car. When the chute 5 and the blade carried thereby are not in use for removing material from the third rail, the arm 3 may be swung in an upward direction, whereby the chute 5 is elevated above the third rail and the dog 19 engages in the notch 18 and 60
65 holds the arm and the chute in the said elevated position. While the arm 3 is in its lowermost position it is (supported as hereinbefore stated) in a resilient manner under the influence of the spring 15, consequently the blade 10 which is carried by the chute may follow the under surface of the third rail 7 in the event that the third rail rises or falls with relation to its normal position with respect to the track rails over 65 which the truck 1 travels. When the arm

3 is in its lowermost position, the free end of the pawl 21 rests against the rear side of the extremity 12 and below the lug 13 thereof. In the event that the blade should become displaced from the third rail 7, the 70 arm 3 cannot fly suddenly in an upright direction in view of the fact that the lug 13 will encounter the upper end of the pawl 21 and thus the upward swinging movement of the said arm is checked. When it is desired to elevate the outer end of the arm 3, 75 an operator grasps the knob 23 and moves the pawl 21 upon its pivot out of the path of movement of the lug 13 and against the tension of the spring 22. Thus the outer 80 end of the arm 3 may be swung in an upward direction and the dog 19 engaged in the notch 18 as hereinbefore described. When the arm 3 is swung from its uppermost position to its lower position, the end 85 of the extremity 12 moves in an upward direction along the forward side of the pawl 21 and pushes the free edge of the said pawl back until the lug 13 moves beyond the upper end of the said pawl. When this happens the upper end of the pawl 21 is forced against the rear side of the extremity 12 under the influence of the spring 22 and the said arm 3 is held in its lowered position until such time as the upper edge of the 95 pawl 21 is removed from the path of movement of the lug 13 when the said arm and its attachment may be raised to their elevated positions as hereinbefore described.

Having described the invention what is 100 claimed is:—

1. In combination with a truck a third rail cleaner comprising a bracket attached to the truck, an arm pivotally attached to the bracket, a chute carried by the arm and means carried by the chute for moving along and in contact with the third rail. 105

2. In combination with a truck a third rail cleaner comprising a bracket attached to the truck, an arm pivotally mounted in the bracket, means mounted in the bracket for resiliently supporting the arm, a chute carried by the arm and means carried by the chute for moving along and in contact with the third rail. 110

3. In combination with a truck a third rail cleaner comprising a bracket attached to the truck, an arm pivotally mounted in the bracket, a chute carried by the arm and curved longitudinally, said chute being provided at its lower forward end with a nose portion, a blade mounted upon the said nose portion and adapted to move along and in contact with the third rail. 115

4. In combination with a truck a third rail cleaner comprising a bracket attached to the truck, an arm pivoted in the bracket, a chute carried by the arm, said chute being provided at its lower forward end with a nose having at its upper side an opening, 120

guide strips mounted upon the nose, a blade mounted upon the nose between the said guide strips and having an opening adapted to register with the opening in the nose, said blade being convexed longitudinally.

5. In combination with a truck a third rail cleaner comprising a bracket attached to the truck, an arm pivotally mounted in the bracket, a chute carried by the arm, means carried by the chute for moving along and in contact with the third rail, spring means for supporting the arm in its lowered position, and a dog pivotally mounted upon the bracket and engageable with the arm

15 to hold the same in an elevated position.

6. In combination with a truck a third rail cleaner comprising a bracket attached to the truck, an arm pivotally connected with the bracket, a chute carried by the 20 arm, means carried by the chute for moving along and in contact with the third rail, the said arm being provided at its inner end

with an angularly disposed extremity having a lug, a spring pressed pawl pivotally mounted upon the bracket and engageable 25 with the arm to hold the same in an elevated position, a spring pressed block movably mounted in the bracket and adapted to be engaged by the angular extremity of the arm whereby the said arm is resiliently 30 supported while in its lowered position, and a spring pressed pawl pivotally mounted upon the bracket and having an edge portion adapted to lie under the lug of the extremity of the arm and normally spaced 35 from the same.

In testimony whereof we affix our signatures in presence of two witnesses.
